UNITED STATES PATENT OFFICE.

ERNEST DAVIS, OF CHICAGO, ILLINOIS, ASSIGNOR, BY MESNE ASSIGNMENTS, TO THE PROSPERITY COMPANY, INC., OF SYRACUSE, NEW YORK, A CORPORATION OF NEW YORK.

PRESSING-MACHINE MECHANISM.

Application filed August 5, 1924. Serial No. 730,322.

This invention relates to pressing machines, such as garment and laundry pressing machines, of the type in which the press head is closed by a mechanism including a 5 crank or other rotary eccentric means to open and close the movable press head and has for its object a motion transmitting mechanism by which the press is moved with accelerated motion from its open position to 10 an intermediate position, and with decreasing motion from such intermediate position to final pressing position, or essentially a mechanism by which the press is closed by a decreasing leverage between the driving 15 and driven parts, so that speed is translated into power at the beginning and end of the opening and closing movements and particularly at the end of the closing movement, and also owing to the leverage ratio at the 20 end of the closing movement the press is closed with relatively great pressure without increasing the load suddenly on the prime mover. Also the leverage ratio at the start 25 of the closing movement of the press is small, so that, the press head starts without throwing a load suddenly on the prime mover.

The invention consists in the novel features and in the combinations and constructions hereinafter set forth and claimed.

In describing this invention reference is had to the accompanying drawings in which like characters designate corresponding parts in all the views.

Figures 1 and 2 are respectively elevations of a pressing machine embodying my invention, the press being shown as open in Fig. 1, and as closed in Fig. 2.

Figure 3 is a detail view of the half revolution or periodic clutch mechanism.

Figure 4 is a detail view of the lever for operating the clutch mechanism.

Figure 5 is a diagrammatic view illustrating the pressure line, and the position of the elliptical gears, during a quarter revolution of the driving shaft.

This pressing machine comprises generally cooperating pressing elements, one movable toward and from the other, and means 50 for actuating the movable element, including rotary eccentric means, constructed to move from starting position when the press is open with low leverage ratio and with accelerated motion and increased leverage

ratio to intermediate position and with decreasing motion and leverage ratio from intermediate position to its position when the press is in final closed position.

I have here illustrated my invention, as embodied in that type of pressing machine including a stationary pressing element or buck 1, a movable element or head 2, movable toward and from the buck 1, the buck 1 being mounted on a suitable frame 3, and the head 2 being carried by a yoke or lever 4 pivoted between its end at 5 to a standard 6 rising from the frame, and the head 2 being carried by the front arm of the lever, and the actuating means being connected to the rear arm of the lever.

In the machine here illustrated this actuating means comprises a toggle including links 7, 8, pivoted together at 9, the link 7 being pivoted at 10 to the rear arm of the lever 4, and the link 8 being pivoted at 11, to the base of the machine, the toggle being movable from its folded position shown in Fig. 1, to straightened position shown in Fig. 2. The toggle is actuated by a crank, and a connecting rod between the crank and the toggle, the crank being in nearly a straight line with the connecting rod when the crank is in its starting position, and at the end of its throw or after it has made a half revolution. By the use of an ordinary crank mechanism the leverage ratio remains the same and hence throws unequal loads back on the prime mover as a start and stop electric motor or a start and stop shaft, especially during starting when the prime mover must overcome the inertia of the movable element and the motion transmitting mechanism and at the end when final pressure is being applied and again when starting to open the press. Hence the prime mover, owing to the high leverage ratio, is ineffective to apply full power and heavy pressure when the press is closed.

By my invention, owing to a change of the leverage ratio between the driver and the crank shaft speed is converted into power as the press approaches closed position. This change of leverage is in effect the same as starting with a comparatively short crank, gradually lengthening the crank, and then gradually decreasing the length of the crank.

In the illustrated embodiment of my in-

vention this effect is brought about by the use of elliptical gears for transmitting the motion from an intermittently movable driver to the crank shaft.

5 12 designates the drive shaft; having an elliptical gear 13 thereon, 14 designates the crank shaft, having a crank 15 thereon, and also an elliptical gear 16, the elliptical gear 16 meshing with the gear 13, the gears being 10 normally arranged with the minor axis of the drive gear 13 in line with the major diameter of the elliptical gear 16, and the major diameter of the gear 16 being arranged at an angle to the crank 15.

15 17 is a connecting rod connecting the crank 15 and the joint 9 of the toggle. The crank 15 is arranged, so that, it is substantially in alinement with the connecting rod at the beginning and end of the throw thereof. That is, it is in the position shown in Fig. 1, at the beginning of the closing movement, and in the position shown in Fig. 2 at the end of the closing movement of the press. Thus the gear or leverage 20 ratio between the gears 13 and 16 is normally, say, 1 to 3, and during the half revolution the gears move gradually from 1 to 3 to 3 to 1, and back from 3 to 1 to 1 to 3, as shown in Fig. 5. The gear ratio being 25 30 low, say 1 to 3 when the final heavy pressure is applied no sudden strain is thrown back on the power and final heavy pressure is gained by transfer into power and a heavy fly wheel is not necessary, the operation 35 of the prime mover is uniform and the consumption of current less when an electric motor is used as a prime mover.

The shaft 12 is mounted in a suitable housing 18 supported by the main frame, and 40 the crank shaft is also mounted in suitable bearings carried by the main frame. The shaft 12 is driven by a constantly running electric motor and periodic or half revolution clutch mechanism between the motor 45 and the shaft 12. 19 designates the motor which may be of any suitable form, size and construction. 20 is the armature shaft of the motor, it having a worm 21 thereon which meshes with the worm gear 22 mounted 50 on the shaft 12 to rotate about the same. This gear 22 is located within the housing 18.

The periodic clutch mechanism here shown comprises a clutch section which is shiftable manually to its "in" position and automatically to its "out" position at the end of each half revolution of the shaft 12. The clutch mechanism here shown includes a shiftable section 23 mounted on the shaft 12 to rotate therewith and to shift axially 55 thereof, pins 24 movable by the section 23 into and out of holes 25, in the web of the gear 22, a disk 26 mounted on the shaft 12 and having holes for guiding the pins 24, a pressure ring 27 thrusting against shoulders 28, on the pins, light springs 27^a be-

tween the pressure ring and the shiftable section 23, and a main spring 23^a acting on the section 23 to thrust it "out."

The section 23 is operated to its "in" position by a shifter arm 29 mounted on a rock 70 shaft 30 journalled in the casing 18, the arm 29 thrusting against the hub of the section 23 and a second rock arm 31 mounted on the shaft 32 carried by the upper part of the frame 3, and having an arm 33 thereon, coacting with the arm 31, and a handle lever 34 mounted on the shaft 32. The arm 33 is shaped to house the lever 31, and is provided with a shoulder 35, coacting with the shoulder 36, on the lever 31, these shoulders 35, 36, being so arranged that depressing of the handle 34 causes the shoulder 35 to thrust against the shoulder 36 and operates the arm 31, so that, the rock shaft 30 is rocked to cause the shifting lever 29 to 75 throw the clutch section 23 to the left against the action of the main spring 23^a, thus moving the pins 24 into the holes 25 fixed to the worm gear 22. After the arm 31 has been moved, the shoulder 35 passes over the shoulder 36, so that, the clutch cannot be held in by the operator holding his hand on the handle 34. When the operator releases his hand from the lever 34 it returns to its normal position under the weight of the arm 80 33 or by a spring, and the shoulder 35 ratchets past the shoulder 36. The light springs 27^a permit the pins to yield momentarily when not in alinement with the holes 25.

85 The clutch is held to its "in" position by a cam rim 38, mounted in the housing 18 concentric with the shaft 12 and followers 39, on the section 23 and coacting with the cam 38, the cam being formed with diametrically opposite notches 40 for receiving the followers and with plain faces 41 between the notches.

90 The followers are normally arranged in the notches. Upon depression of the handle 100 lever 34 the section 33 is shifted to the left to the "in" position against the action of the spring 23^a, and the pins 24 are shifted into the holes 25 in the worm wheel 22. Hence the shaft 12 commences to rotate with 105 the worm wheel 22, carrying the follower on to the high or plain face 41 of the cam, so that, the clutch section 23 is held "in" by the plain faces of the cam during a half revolution or until the followers again come 110 into alinement with the notches, whereupon the spring 23^a shifts the clutch section 23 to the right to its "out" position disconnecting the shaft 12 from the worm wheel 22.

115 The construction of this clutch mechanism 120 forms no part of this invention.

What I claim is:

125 1. In a pressing machine, cooperating pressing elements, one movable toward and from the other, and means for actuating the 130

- movable element, comprising a shaft, having a crank and a connecting rod mounted on the crank, the connecting rod and crank being arranged substantially in radial alignment when the press is open and when the press is closed, an intermittently rotatable drive shaft, an elliptical gear mounted on the crank shaft with its major axis at an angle to the radius of the crank, an elliptical gear mounted on the drive shaft and meshing with the former elliptical gear, the gears being normally arranged with the minor diameter of the gear on the drive shaft in line with the major diameter of the gear on the crank shaft, and means for causing the driving shaft to intermittently make half revolutions.
2. A pressing machine, comprising cooperating pressing elements, one movable toward and from the other, means for actuating the movable element, comprising a toggle movable into straightened position to close the press, a crank shaft having a crank thereon, a connecting rod connecting the crank and the toggle, the connecting rod and the crank being movable into a straight line to close the toggle to a substantially straight line, an elliptical gear mounted on the crank shaft, with its major diameter at an angle to the radius of the crank, an intermittently rotatable drive shaft, and an elliptical gear thereon meshing with the former elliptical gear thereon, the elliptical gears being normally arranged with the minor diameter axis of the driving gear in line with the major diameter of the driven gear, and means for causing the drive shaft to make a half revolution during each operation.
- In testimony whereof, I have hereunto signed my name, at Syracuse, in the county of Onondaga, and State of New York, this 24th day of July, 1924.

ERNEST DAVIS.
